(57) **CLAIM**

The ornamental design for a vehicle foglight bezel, as shown and described.

DESCRIPTION

FIG. 1 is a left side elevational view of a left vehicle foglight bezel (the right vehicle foglight bezel being a mirror image and is not shown);

FIG. 2 is a right side elevational view of the vehicle foglight bezel;

FIG. 3 is a front elevational view of the vehicle foglight bezel;

FIG. 4 is a top plan view of the vehicle foglight bezel;

FIG. 5 is a bottom plan view of the vehicle foglight bezel;

FIG. 6 is a perspective view of the vehicle foglight bezel; and,

FIG. 7 is another perspective view of the vehicle foglight bezel.
